KEY-TYPE RAIL ANCHOR

Arthur I. Appleton, Northbrook, Ill.

Application January 27, 1956, Serial No. 561,739

2 Claims. (Cl. 238—315)

The present invention relates to rail holding appliances and, more specifically, to a novel rail anchor adapted to prevent longitudinal displacement of railroad rails under traffic.

The tendency of railroad rails to move longitudinally or "creep" ahead of a train in the same direction as the train is traveling has long been known. Heretofore, the approach to this problem has been to provide rail anchors which grip or clamp the rails to prevent such displacement, each anchor acting in one direction. The necessity for gripping the rail at all times, including periods of rest and periods of traffic, has introduced complexity and expense into the construction of conventional rail anchors.

One object of the present invention is to provide a novel rail anchor capable of opposing longitudinal rail displacement or creepage in two directions rather than in just one direction.

Another object is to provide a rail anchor of the character just set forth and which takes full advantage of existing rail bases and tie plates.

A further object is to provide a rail anchor of the foregoing type comprising a single unit of simple, economical, and rugged construction.

Other objects and advantages of the invention will become apparent as the following description proceeds, taken together with the accompanying drawings, wherein:

Figure 1 is a fragmentary plan view showing a pair of rail anchors, each embodying the invention, installed on a railroad rail.

Fig. 2 is an enlarged fragmentary vertical sectional view through one of the rail anchors and the rail of Fig. 1, such view being taken in the plane of the line 4—4 as the rail anchor is being installed in place.

Fig. 3 is a view similar to Fig. 2 but showing the rail anchor a step further toward its fully installed position.

Fig. 4 is an enlarged vertical sectional view taken through the rail and rail anchor assembly of Fig. 1 along the plane of the line 4—4.

Fig. 5 is a further enlarged transverse sectional view through one of the rail anchors shown in Fig. 4, such view being taken in the plane of the line 5—5.

While the invention is susceptible of various modifications and alternative constructions, a preferred embodiment has been shown in the drawings and will be described below in considerable detail. It should be understood, however, that there is no intention to limit the invention to the specific form disclosed, but on the contrary, the intention is to cover all modifications, alternative constructions and equivalents falling within the spirit and scope of the invention as expressed in the appended claims.

Referring more particularly to Figs. 1 to 4, inclusive, the invention is there exemplified in an illustrative rail anchor 10 and in this instance two such anchors are shown, one on each side of the rail. Each anchor is adapted to engage a rail 11 and oppose longitudinal creepage of the same. Although the anchors 10 are shown

in close proximity to each other, it will be appreciated that a wide variety of patterns may be followed for installing the anchors along the rail.

By way of background, it might be noted that rail 11 is of conventional form, comprising a head 12, web 14 and a flange or base 15. The rail is mounted on a tie plate 16 which, in turn, is mounted on a conventional wood cross tie 18. In this case, the tie plate 16 has a cambered seat 19 which carries the rail base 15, the seat 19 being situated between laterally spaced, upstanding ribs 20. Immediately adjacent the seat 19, the tie plate 16 is provided with the usual four substantially square holes 21 for receiving the hold-down spikes which engage the rail base. The plate 16 may also have additional holes 22 for spiking it directly to the tie, independently of the rail hold-down spikes. While four spike holes 21 are customarily provided adjacent the rail, it is common practice to use only two spikes, one on each side of the rail base. This leaves two spike holes 21 normally vacant.

In conformity with the objectives set forth earlier herein, each rail anchor 10 is fashioned as a single, self-contained unit which is adapted to oppose longitudinal displacement or creep of the rail in either direction, rather than in one direction only as in the case of conventional rail anchors now in widespread commercial use. This is accomplished, moreover, by taking advantage of structural features already present in the rail and tie plate.

Referring more particularly to the drawings, it will be noted that the rail anchor 10 comprises a head 24 having a depending stud 25 adapted to fit into a vacant spike hole 21 of the tie plate. The head 24 is relatively large and heavy compared to the head of a common rail spike. The stud preferably has a cross section comparable to that of the hole 21 but slightly smaller so that it has at least some clearance. On the side adjacent the rail base, the stud 25 has a shoulder 26 which is adapted to preclude withdrawal of the stud from the spike hole 21 after the rail anchor has been installed. The stud 25 may also have one or more additional shoulders 26a similar to the shoulder 26 and adapted to accommodate tie plates of different thicknesses. To facilitate installation and initial positioning of the rail anchor 10, the depending end of the stud 25 is tapered sharply on two opposed sides and tapered to a lesser extent on the remaining two sides, thus giving the stud a wedgelike point 28. The point 28 is adapted to penetrate the tie 18 permitting the anchor to be driven into position by striking the top of the head 24 with a sledge hammer. The point 28 is offset with respect to the vertical axis of the stud 25 and is situated on the same side of such axis as the shoulder 26. Thus, as the anchor is driven into the tie, the stud 25 and shoulder 26 are caused to drift laterally so that the shoulder 26 will ultimately lie under the bottom edge of the tie plate. The driving of the anchor into its initial position is also facilitated by the provision of a top surface 29 on the head and which is approximately perpendicular to the longitudinal axis of the stud 25.

In order to effect engagement between the rail anchor 10 and the rail 11, the anchor head 24 is extended laterally with respect to the stud to overlie the rail base 15. The head is also provided with a transverse keyway 30 which extends in the same direction and slidably houses a key 31. In the present instance, both the keyway 30 and the key 31 are of substantially rectangular cross section. The key 31 is somewhat longer than the keyway 30 so as to project beyond the head 24. At the end of the key 31 which projects toward the rail 11, there is provided a depending foot 32 which is adapted to engage the upper surface of the rail base 15. Due to the relative shapes and proportioning of the parts, such

engagement will take place after the rail anchor 24 is driven into the tie 18 as far as it will go. Such engagement is then reinforced by driving the key 31 toward the rail and causing the foot to climb the sloping surface of the rail base 15, biting in as it goes.

For the purpose of preventing retrograde movement of the key 31 after the same has been driven tight, resort is had to a relatively simple but highly effective detent means between the head 24 and the key 31. Accordingly, the portion of the head projecting toward the rail is provided with a pair of resilient arms 34 which straddle the key and keyway 30, 31 and bear against opposed sides of the key. The opposed sides of the key 31 are formed with parallel ridges and grooves 35, 36 which extend approximately vertically and cover a substantial portion of the length of the key. These ridges and grooves coat with the resilient arms 34 in such a way that the arms 34 readily spread apart as the key 31 moves toward the rail but tend to lock or jam in response to a force tending to move the key 31 away from the rail.

The operation of the rail anchor 10 is shown sequentially in Figs. 2, 3 and 4 and a brief synopsis thereof might be helpful at this point. Initially, the anchor 10 is placed with its stud 25 extending into a vacant spike hole 21 in the tie plate, as shown in Fig. 2. The key 31, which is held captive in the keyway 30 by the arms 34 and by the foot 32, is preferably in its outermost position. The anchor 10 is then driven into the tie by the use of a sledge hammer, the top 29 of the head serving as an anvil for engagement with the hammer. Due to the offset of the point 28, the lower end of the stud 25 begins to drift toward the rail 11, eventually carrying the shoulder 26 under the bottom of the tie plate 16 due to the resiliency of the wood in the tie 18. Movement of the anchor 10 into the tie 18 finally ends when the foot 32 of the key engages the upper surface of the rail base 15, as shown in Fig. 3. The installer then hammers on the outer end of the key 31, driving the same toward the rail and causing the foot 32 to climb the sloping upper surface of the rail base 15. By reason of the positive locking engagement between the shoulder 26 and the underside of the tie plate 16, and also the binding of the stud 25 in the hole 21 due to canting of the stud therein, the head 24 becomes rigidly fixed with respect to the tie plate 16 and the rail base 15. Consequently, as the key 31 is driven toward the rail, the foot 32 bites into the upper surface of the rail base with increasing force, effectively resisting movement of the rail in either direction.

In the event that it should be necessary to remove the anchor 10 after the same has been installed, this may be accomplished by the use of a conventional spike puller. For this purpose, the head 24 is extended in a direction parallel to the rail so as to project well beyond the stud 25. By the same token, when completely installed there is a sufficient space left between the underside 38 of the anchor head and the upper face of the tie plate 16 to insert the jaws of the spike puller therebetween. Application of force to the spike puller serves to place an

elevating force on that portion of the head remote from the rail and, if sustained, causes the shoulder 26 to slip out from under the bottom of the tie plate 16. The inner edge of the shoulder may, of course, become somewhat deformed or mashed over in this process. Such a force is, of course, only the result of using the spike puller and is not encountered in normal operation of the anchor 10.

I claim as my invention:

1. A rail anchor for holding a railroad rail against longitudinal creepage in two directions, said rail being mounted on a tie with a tie plate interposed between the rail base and the tie and having spike holes therein, said anchor comprising, in combination, a head having a keyway extending therethrough, a stud fixed to said head in depending relation therewith for extending through one of the spike holes of said tie plate into engagement with the tie, a key slidably mounted in said keyway and including means for engaging the rail base, said key being greater in length than said keyway, means defining a series of spaced apart ridges on opposite sides of said key, and a pair of resilient arms projecting from said head in straddling relation with the keyway and said key for engaging said ridges in a manner permitting movement of said key in one direction but opposing retrograde movement of said key.
2. A rail anchor for holding a railroad rail against longitudinal creepage in two directions, said rail being mounted on a tie with a tie plate interposed between the rail base and the tie and having spike holes therein, said anchor comprising, in combination, a head having a keyway extending therethrough, a stud fixed to said head in depending relation therewith for extending through one of the spike holes of said tie plate and into engagement with the tie, means defining at least one lateral shoulder on said stud for engaging the underside of the tie plate upon installation of said anchor, means defining an apex at the depending end of said stud, said apex being offset from the vertical axis thereof in the direction of said lateral shoulder, a key slidably mounted in said keyway, a depending foot fixed to one end of said key for engaging the rail base, means defining a series of spaced apart ridges on opposite sides of said key, and a pair of resilient arms projecting from said head in straddling relation with the keyway and said key for engaging said ridges in a manner permitting movement of said key in one direction but opposing retrograde movement of said key.
